UNITED STATES PATENT OFFICE.

JAMES T. ANDREW, OF MONTGOMERY, ALABAMA.

SAFETY APPLIANCE FOR RAILROAD-CARS.

No. 898,165.

Specification of Letters Patent.

Patented Sept. 8, 1908.

Application filed August 7, 1908. Serial No. 447,361.

To all whom it may concern:

Be it known that I, JAMES T. ANDREW, a citizen of the United States, residing at Montgomery, in the county of Montgomery and State of Alabama, have invented certain new and useful Improvements in Safety Appliances for Railroad-Cars; and I do hereby declare the following to be a full, clear, and exact description of the invention, such as will enable others skilled in the art to which it appertains to make and use the same.

My invention relates to safety appliances for railroad cars and constitutes one feature of a double safety device, the other feature of which is more fully described and particularly claimed in my co-pending application filed April 22, 1908, Serial Number 429,785.

The object of my invention is to provide means actuated by the derailment of the train to operate the air brake system and at the same time signal that a derailment has occurred.

To these ends my invention consists in the details of construction and in the arrangement and combination of parts to be herein-after more fully set forth and claimed.

In describing the invention in detail reference will be had to the accompanying drawing wherein like characters of reference denote corresponding parts in the several views and in which:—

Figure 1 is an end elevation of a portion of a car truck with my invention applied thereto, same being partly in section. Fig. 2, an elevation in section of the back of the journal box looking outward, and Fig. 3, a diagrammatic view showing in full lines means automatically actuated by derailment to operate valves of the Westinghouse air brake system.

Referring to the drawings, 1 represents the rails; 2, the axle of an ordinary car truck; 3, the wheels; 4, the journal boxes; and 5, the ordinary pedestals of a car truck.

Secured to the journal box by means of straps 7, is a safety frame 8, which is secured to the pedestals by the slip bolts 10, and to the equalizer beam (not shown). In this safety frame 8, is carried the safety roller 11, the frame being provided with downwardly depending curved projections 12, forming an open cylinder bearing for the reception of the said roller, thereby forming in reality a

cylindrical safety frame. The roller 11 is provided on its inner end with an integral 55 collar 13, and on its outer end with a removable collar 14, there being a cotter pin 15, passing through the end of the roller 11, to hold the collar 14 in place. In assembling these parts, the roller is placed in the open 60 cylinder bearing, as shown, before the safety frame 8 is secured to the journal box, pedestals, and equalizer beam, not shown, and the cotter pin passed through the hole in the end of the roller provided for the purpose. When 65 in place this roller will stand about three inches above the top of the rail, and the open cylinder being larger than said roller, will allow the same to rise about one half an inch should contact with the rail occur, and 70 for a purpose to be described hereinafter.

On the car axle 2, between the wheels 3, is placed a sleeve 18 made in halves, provided with lugs 19, tapered journal bearings 20, and with shoulders 21, all as shown.

On the bearings 20, are the safety wheels 22, having double flanges 23 and 24. These wheels may be either split wheels, or made in one piece. In either case the flanges 23 are more tapered than the flanges 24, for a 80 purpose that will presently appear. The lugs 19 serve to secure the halves of the sleeve together, and to make the same rigid with the axle 2.

Over each sleeve 18 is secured two of the 85 safety beam supports 25, and these supports are provided with the straps 26, encircling said sleeve and having the bolts 27 passing through the flanges 28 integral with said supports 25, the whole loosely encircling the 90 sleeve 18 as shown.

Extending between the journal box 4 and the wheel 3, is a plunger rod 35, passing through guides 36. This rod at the upper end actuates a plunger 37 which controls a 95 valve in the casing 38, on the end of the pipe 39, which connects with the train line of the air piping 40, which operates the brakes. This piping 40 is also provided with the valve levers 41, having the connections 42, with 100 the levers 43, pivoted at 44 to the car body, and extending into the path of the wheels 22 for a purpose that will be presently explained. The safety and signal levers 43, are also provided with the connections 45 leading 105 to the lever 46 of the engineer's and conduc-

tor's whistle signal 47, having the well known pipe connection 48 with the cab of the engine. The lower end of the rod 35, is provided with a suitably shaped shoe 49, with 5 which the collar 13 of the roller 11 contacts.

The operation is as follows:—When the flange of a wheel 3, rises to cross a rail 1, during a derailment of the train, the safety roller 11 on the one side and the safety wheel 22 10 on the other, of necessity likewise rises; and a roller on one side of the truck and a wheel 22 on the other side of the truck moves toward the rails, and of necessity contacts therewith when the flanges of the wheel 3 15 have crossed the rails and fall on the other side thereof. The lower contacting surfaces of both the rollers 11 and wheels 22 are so disposed that they will strike the top of the rails before the flanges of the wheels 3 reach 20 the spikes or ties, so that the train for the time being will be supported by reason of one of the rollers 11, on one side, and one of the wheels 22 on the other side of the truck contacting with the tops of the rails. In the 25 meantime, in the case of a derailment the trucks, and with them the safety wheels 22 are given a sharp twist, and therefore have a considerable movement relative to the car body, from which the signal levers are sup- 30 ported. Consequently one of the safety brake and signal levers 43, which are pivoted to the car body, is struck by one of the wheels 22, as it is carried to one side or the other of the track, the air brakes are applied, 35 and the engineer's whistle blown through the connections shown. When going around curves the trucks also move relatively to the car body, but not to such an extent as in the case of a derailment. Therefore, to prevent 40 the levers 43 from being operated in such cases, they are placed just far enough from said wheels as not to be moved thereby, except in the case of the sharper turns or twists given the trucks when the wheels leave the 45 rails.

While I have shown a preferred embodiment of my safety appliance, it is evident that many changes may be made by those skilled in the art in the general form and arrangement of the parts without departing from the spirit of the invention, and therefore I would have it understood that I do not limit myself to the precise details set forth.

What I claim is:—

55 1. In a car truck employing a journal box, an equalizer beam and the usual pedestals, the combination of a safety frame secured to said beam, pedestals and box, and thereby adapted to hold up said box in case of accident; a bearing in said frame; a safety roller in said bearing and smaller than the same; and means controlling the brakes adapted to be operated by said roller in case of accident, substantially as described.

65 2. In a car truck employing a journal box,

an equalizer beam and the usual pedestals, the combination of a safety frame secured to said beam, pedestals and box, and thereby adapted to hold up said box in case of accident; a bearing in said frame consisting of an open cylinder; a safety roller, provided with collars 13 and 14, in said bearing and smaller than the same; and means controlling the brakes adapted to be operated by one of said collars on said roller in case of accident, substantially as described. 70 75

3. In a car truck provided with the usual wheels and axle, the combination of a split sleeve surrounding said axle; a pair of safety wheels on said sleeve inside said usual wheels and provided with outer beveled flanges 23, inclined treads and flanges 24; safety frames outside said usual wheels, provided with bearings; safety rollers in said bearings; means operated by said safety wheels for controlling the application of the brakes in case of accident; and means operated by said rollers for also applying the brakes, substantially as described. 80 85

4. In a car truck provided with the usual wheels and axle, the combination of a split sleeve surrounding said axle; a pair of safety wheels on said sleeve inside said usual wheels and provided with outer beveled flanges 23, inclined treads and flanges 24; safety frame 95 outside said usual wheels, provided with bearings; safety rollers in said bearings; means comprising levers operated by said safety wheels for controlling the application of the brakes, and sounding an engineer's signal in case of accident; and means operated by said rollers for also applying the brakes, substantially as described. 100 105

5. In a car truck provided with the usual wheels and axle, the combination of a split sleeve surrounding said axle; a pair of safety wheels on said sleeve inside said usual wheels and provided with outer beveled flanges 23, inclined treads and flanges 24; safety frames outside said usual wheels, provided with bearings; safety rollers in said bearings; means comprising levers operated by said safety wheels for controlling the application of the brakes, and sounding an engineer's signal in case of accident; and means operated by said rollers for also applying the brakes, 110 115 comprising a rod 35 provided with a shoe 49, and a valve substantially as described.

6. In a car truck provided with the ordinary wheels and axle, the combination of auxiliary wheels and rollers adapted to retain and support the truck on the rails upon derailment of the ordinary wheels, and means controlling the brakes adapted to be operated by said auxiliary wheels and rollers 120 125 in case of derailment, substantially as described.

7. In a car truck provided with the ordinary wheels and axle, the combination of auxiliary wheels and rollers adapted to re- 130

tain and support the truck on the rails upon
derailment of the ordinary wheels, and
means comprising levers operated by the
auxiliary wheels and rollers for controlling
the application of the brakes, and sounding
an engineer's signal in case of derailment,
substantially as described.

In testimony whereof, I affix my signature,
in presence of two witnesses.

JAMES T. ANDREW.
